UNITED STATES PATENT OFFICE.

SVEN AUGUST ESKILSON, OF STOCKHOLM, SWEDEN, ASSIGNOR TO AKTIEBOLAGET
SALENIUS VERKSTÄDER, OF STOCKHOLM, SWEDEN, A CORPORATION OF
SWEDEN.

NECK-BEARING.

1,310,794.

Specification of Letters Patent. Patented July 22, 1919.

Application filed May 14, 1919. Serial No. 297,111.

To all whom it may concern:

Be it known that I, SVEN AUGUST ESKILSON, a subject of the King of Sweden, and resident of Torstensonsgatan 4, Stockholm, 5 in the Kingdom of Sweden, have invented certain new and useful Improvements in Neck-Bearings, of which the following is a specification, reference being had therein to the accompanying drawing.

10 This invention relates to a yielding neck bearing, adapted especially to the spindle of the drum in cream separators. As a yielding member between the sleeve of the spindle and for instance the frame of the separator the well known arrangement of a wire or strip of metal or any other springy material and bent into a zigzag shape is used, which is shaped into a ring and at the ends of each part bears against the said 15 sleeve and at an intermediate portion of the parts bears against the frame or vice versa. According to the invention the parts of the said ring extend in an oblique direction peripherically from the bends, connecting the 20 parts, toward an intermediate portion of the parts, the said portion being preferably straight. Owing to this arrangement of the parts the yielding capacity of the ring is improved and besides the intermediate portion 25 of the parts bears against the sleeve or the frame respectively in a more suitable manner than hitherto.

In the accompanying drawing Figure 1 is a side view partially a section of a neck bearing arranged in accordance with this invention. Fig. 2 is a section on the line 2 to 2 of Fig. 1.

1 is the sleeve of the spindle and 2 may designate the frame of the separator. 3 is 40 the yielding ring, formed of a wire bent into a zigzag shape and then into a ring. As shown in Fig. 1 the wire is bent in such manner, that its parts extend in an oblique direction peripherically with relation to the 45 ring, from their ends toward their intermediate portion. The intermediate portion of each part is preferably straight for a suitable length, as shown. In the drawing the ends of the parts bear against the sleeve 50 1, while their intermediate portion bears against the frame 2. The wire may, however, be so bent, that the ends of the parts

bear against the frame and their intermediate portions bear against the sleeve.

Owing to the described arrangement of 55 the parts of the ring the parts do not yield radially or straight toward and from the center line of the bearing, as is the case in rings hitherto used, but each part swings about a line, which connects the ends of the 60 parts, or swings on the ends of the parts as supporting points. Consequently, the yielding evidently is considerably softer than in rings hitherto used and made of the same 65 material and having the same dimensions. 70 Owing to the fact that the parts are straight at their intermediate portions and consequently bear against the frame by means of a considerable portion of their length, the wear of the parts is reduced and the parts 75 do not tend to cut into the frame, as, on the other hand, is the case, when the parts respectively bear against the frame substantially at one point.

Having now described my invention, what 75 I claim as new and desire to secure by Letters Patent is:

1. In a neck bearing the combination of a sleeve, an outer bearing surface, and a yielding ring-shaped member inclosing the 80 said sleeve and consisting of a wire or strip of metal or the like bent into a zigzag shape, the parts extending in an oblique direction peripherically from the bends connecting the parts, to the intermediate portions of the 85 parts, and bearing at the ends against the said sleeve and at the intermediate portion against the said bearing surface or vice versa.

2. In a neck bearing the combination of 90 a sleeve, an outer bearing surface, and a yielding ring-shaped member inclosing the said sleeve and consisting of a wire or strip of metal or the like bent into a zigzag shape, the parts of the ring extending in an oblique 95 direction peripherically from the bends, connecting the parts, to an intermediate straight portion of the parts, and bearing at the ends against the said sleeve and at the intermediate portion against the said bearing surface or vice versa. 100

In witness whereof I have hereunto signed my name.

SVEN AUGUST ESKILSON.
